LADY'S GARMENT CONSTRUCTION

Philip Wenett, New York, N. Y.

Application October 1, 1937, Serial No. 166,782

1 Claim. (Cl. 2—71)

The present invention relates to a feminine clothing construction and it particularly relates to a combined outer and inner garment particularly designed for afternoon or evening wear.

In tailored garments for sport, street, afternoon and evening wear there is often the difficulty that the undergarments do not conform to, nor satisfactorily fit under the outer garment, with the result that the outer garment is often disfigured and the wearer is made quite uncomfortable due to twisting of the undergarment in respect to the outer garment and/or the body.

This difficulty is particularly apparent in one piece dresses where the suspension is primarily from the shoulders of the wearer and where the dress has been tailored to fit the woman's body as in evening gowns.

It is among the objects of the present invention therefore to provide an improved garment for feminine wear, and particularly an improved tailored garment for street, sport, afternoon or evening wear which will be devoid of the difficulties above mentioned, which will eliminate substantial relative movement between the undergarment and the outer apparel, which will avoid deformation of the tailored line of the outer garment and at the same time assure greater comfort to the wearer.

Another object of the present invention is to provide an improved garment construction for women, which may be inexpensively manufactured, which will be sanitary, which is particularly adapted for evening wear, which is readily fitted upon the wearer and which may be put on and taken off by the wearer without difficulty and without any manipulations other than customarily at present employed with other types of garments.

Other objects will be obvious or will appear during the course of the following specification.

In accomplishing the objects of the above invention, it has been found desirable to design the outer gown and the inner gown in such a manner that there will be a common placket or opening in the side or back of the combined garment, the inner garment and the outer garment being sewn together along the edges of the placket and the same fasteners being employed to close the placket in both the inner garment and the outer garment. Depending upon the height of the inner garment and the position of the placket in respect to the waistline of the outer garment, the placket may extend for its lower half or for a major fraction of its length into the upper portion of the inner garment.

In evening dress constructions, which represent a preferred adaptation of the present invention, to which however the invention is by no means restricted, the placket is preferably at one side or in the middle of the back and the lower half of such placket should extend into the inner garment, which conveniently may take the form of a pair of panties with a detachable understrap, removable for washing or cleaning.

In evening gowns where the connection of the upper portion or bodice to the skirt portion is often above the waistline, it is found particularly desirable to extend the undergarment up to said line of connection and to sew the upper edge of the undergarment to the lower edge of the bodice and the upper edge of the skirt of the outer garment along a single seam or by a single or double row of stitching. This seam or stitching may be positioned above the waistline at a position below the bust of the wearer.

This line of attachment may extend upwardly to a peak at an elevated position centrally on the bust of the wearer and then slope downwardly toward the sides of the wearer and across the back of the wearer where it may approach the waistline. In this construction the height of the undergarment will be maximum in the front of the wearer and will be at a minimum at the rear of the wearer with an intermediate height at the sides of the wearer.

An important feature of the present invention resides in the fact that the inner garment is tailored to conform closely to the conformation of the outer garment above the waist of the wearer and is tailored below the waist of the wearer so as to conform more closely to the body than the outer garment.

In the drawing, which illustrates one of the forms of the present invention, to which however the invention is by no means restricted, since many different embodiments and garments could be utilized all within the scope of the present invention:

Fig. 1 is a front view of an evening gown, to which the invention of the present application has been applied, illustrating such gown positioned upon the wearer with a portion of the gown broken away to show the undergarment construction.

Fig. 2 is a back view of the wearer with the gown in position thereon with a portion of the outer garment broken away to show the undergarment construction.

Fig. 3 is a side sectional view upon the line 3—3 of Fig. 1 of the upper portion of the wearer with

the outer and inner garments in vertical section.

Fig. 4 is a fragmentary inside out view of the garment construction with the skirt pulled out at top, removed from the wearer.

5 Fig. 5 is a cross section upon the line 5—5 of Fig. 1 of the garment removed from the wearer.

Referring to the construction of Figs. 1 to 5, the outer garment A is provided with an upper portion or bodice B and a skirt portion C and the inner 10 bifurcated garment D.

As indicated best in Figs. 1 and 2, the outer garment A is attached by line of stitching 10 to the bust portion or bodice portion B of the garment and the upper portion of the dress or gown 15 B—C is tailored, as indicated at 11 and 12 to fit the wearer W.

The gown, as shown in Figs. 1 and 2, is suspended by the straps 13 from the shoulder 14 and has short puff sleeves 15, but it is obvious many 20 different dress constructions and designs may be utilized in connection with the application of the present invention.

It will be noticed that the line of attachment 10 as shown moves up to a peak 16 at the front of 25 the wearer and then descends along the line 17 to a low point 18 at the rear of the wearer, as best shown in Fig. 2.

The bodice portion B in back, shown in Fig. 2, is supported by the crossing straps 13.

30 As shown in Figs. 2 and 3, the placket 19 extends vertically along the middle of the back of the wearer, and although it reaches the highest point 20 of the rear of the garment, it may conveniently be made of shorter length and may also 35 be placed along the side of the garment, if desired.

The undergarment construction D is provided with a bifurcated portion 21 forming the panties which may consist of a fabric cut on the bias and 40 of the same color, but preferably of lesser weight than the outer garment B—C. This inner garment may have central and side seams 22 and a removable strap 23 held in position by the line of detachable fasteners 24. The upper portion 45 of the inner garment D is connected along the stitching line 10 to the outer garment B—C.

Above the waistline, indicated by the dot-and-dash line 25, it is closely conformed to the tailored portions 11 and 12 of the outer garment B—C.

50 The placket 19 extends below the line of attachment 10 and below the waistline 25 of the wearer. Below said line of attachment 10 the inner garment D is attached to the placket 19, as indicated at 26 and 27 in Fig. 4. Opening of the placket 55 19 will also result in opening of the inner garment D, as indicated best in Fig. 4. The upper edge of the inner garment D reaches a peak at the point 16 in Fig. 1 and gradually descends to the point 18 on the back of Fig. 2.

60 By the construction as shown in Figs. 1 to 5, there is obtained a combined panty and outer garment, in which the panty will closely conform to the wearer, will assure a maximum of comfort

and will not deform or change the lines of the dress, even though the wearer thereof may indulge in dancing or other activity. The sanitary character of the garment is assured by removability of the strap 23 and the tailoring of the inner garment above the waist together with the application of the placket to both the inner and outer garment assures most satisfactory fitting of the garment.

It is obvious that many changes may be made 10 in the construction of the outer garment and that the essential features of the present invention may be broadly applied to all types of tailored evening gowns regardless of the specific character.

It is important that the strap 23 be made removable, as indicated upon Figs. 3 and 5, as this permits more ready cleansing of the garment construction. Although the panties D may be made of the same material or of lighter weight material and of the same color as the external garment 20 B—C, they also may be of other materials. In addition the panties may be cut on the bias or in other manners and may be made of different constructions than is specifically shown in Figs. 1 to 4.

25 As stated above, although the present invention has a preferred application to evening gowns and tailored or trimmed dresses, it may also be utilized for store, sport and afternoon dresses.

Many other changes could be effected in the 30 particular features of garment disclosed, and in specific details thereof, without substantially departing from the invention intended to be defined in the claim, the specific description herein merely serving to illustrate certain elements by which, in 35 one embodiment, the spirit of the invention may be effectuated.

What is claimed is:

An evening gown comprising a dress having a 40 skirt portion and a brassière portion having lateral breast portions, said skirt portion and brassière portion being connected together, and said connection being along a line extending from a point between the breast portions downwardly and outwardly on each side to a position adjacent 45 the waistline in the back, a bifurcated undergarment having an upward extension to above the waist line of the dress, said upward extension being attached at its upward edge to the line of connection between the brassière portion and the 50 skirt portion, said attachment being circumferential of the garment, said upward extension of the undergarment being cut to closely conform to the upper portion of the skirt portion above the waist of the wearer, and said bifurcated undergarment being cut to more closely conform to the body of the wearer below the waist line of the wearer than said skirt portion and said gown being provided with a placket extending vertically across the waist line of the wearer, the edges of 60 said undergarment and of said skirt portion being sewn together along the edges of said placket.

PHILIP WENETT.
